EDMUND JOHN THOMPSON, OF OTTAWA, ONTARIO, CANADA

CARBURETER.

1,325,126.

Specification of Letters Patent. Patented Dec. 16, 1919.

Application filed April 21, 1916. Serial No. 92,672.

To all whom it may concern:

Be it known that I, EDMUND JOHN THOMPSON, a subject of the King of Great Britain, and resident of the city of Ottawa, 5 Province of Ontario, Dominion of Canada, have invented certain new and useful Improvements in Carbureters, of which the following is the specification.

This invention relates to improvements in carbureters and particularly to those of the type in which the valve controlling the spray nozzle is automatically controlled by the suction of the engine through the medium of a suction valve which rises and falls with variations in the suction, the said valve also serving to control the proportion of air supply. The objects of the invention are to enable the proportions of air and combustible fluid to be always maintained 20 constant in the varying volumes demanded by the engine, and also to enable the carbureter to be simply and effectively adjusted to suit the requirement of a particular engine whereby it will operate with uniform efficiency at all speeds. Further objects are to provide a carbureter which will work under a comparatively low vacuum, thus increasing the suction stroke pressure on the engine and insuring that the full charge 25 is given to the cylinders at all speeds.

In carrying out these objects, means are provided for adjusting the amount of opening of the valve for a given speed, and also for adjusting the rate at which the air valve 30 will open and close the oil valve to correspond with the change in the speed of the engine.

With the above and other objects in view, the invention consists essentially of the improved construction particularly described and set forth in the following specification and accompanying drawings forming part 40 of the same.

In the drawings, Figure 1 is a vertical section through the improved carbureter.

Fig. 2 is a side elevation of the same.

Fig. 3 is a perspective view of the suction valve.

Fig. 4 is a vertical section of the suction valve.

Fig. 5 is a transverse section of the suction valve on the line 3—3 of Fig. 4.

Fig. 6 is a vertical section through a modified form of the improved carbureter.

Fig. 7 is a side elevation, partly sectional, of the same.

Fig. 8 is a side elevation of the carbureter shown in Fig. 6.

Fig. 9 is a perspective view of the connecting means between the suction valve and the valve for the spray nozzle.

Fig. 10 is a sectional detail of the inclined plane designed to operate the valve in the spray nozzle.

Fig. 11 is a sectional elevation of the contact member engaging the inclined plane.

Like characters of reference refer to like parts in the several figures.

Referring to the drawings, A represents the outer casing shell of suitable shape to contain the working parts, the upper part of which is provided with a tubular outlet neck 10 having a flange 11 to connect with the intake pipe of an engine, the passage 75 through the neck being controlled by a butterfly valve 12.

Mounted within the casing member and vertically reciprocating therein is a suction valve member B formed with a tubular portion 13 which fits the neck 10 and a lower conoidal portion 14 provided with an integral pinion 15 on the lower end thereof adapted to mesh with the pinion 16 rigidly mounted on the spindle 17 rotatably supported by the casing A.

This spindle 17 is held in an adjusted position by a set screw 18 making threaded engagement with the casing A and is further provided on the upper end with a milled head 19 by means of which the said spindle may be manually rotated. The pinion 15 is formed integral with the lower conoidal portion 14 of the suction valve B and is provided with a pair of curvilinear 95 slots or ports 20 through which air is designed to pass in a manner to be made clear hereafter.

The movement of the suction valve by the suction of the engine is effected through the medium of the piston 21 formed on the exterior of the neck 13 and fitting closely to the cylinder 22 formed in the casing, the upper portion of which forms an air chamber 23 which is placed in communication 105 with the suction of the engine through the medium of the small port 24 in the neck 13.

A spray nozzle C is mounted within the valve member B and is of the mushroom type; the head 25, when the valve member 110

is in its lowest position, being adapted to fit closely to the neck 13. Combustible fluid is adapted to discharge around the head through the radial passageways 26 which 5 communicate with the axial supply passage 27 which leads to a constant level supply chamber D.

The bottom of the chamber is slightly above the discharge passageway 26 and is 10 supplied through an inlet passage 28 controlled by a valve 29 which is operated by a float 30 mounted within the chamber D. This float is designed to always maintain a constant head of combustible fluid on the 15 spray nozzle.

To permit access to the passageway 28, a 20 removable plug 31 is provided, which is located directly below the valve 29 thereby affording facilities for inspection of the said 25 valve should such be found necessary. The combustible fluid is delivered from the chamber D through the passageways 32 and 33 to the supply passageway 27, access to the last of which passageway is gained 30 through a removable plug 34.

This supply passageway houses a valve 35 having a tapered lower end designed to control the supply of fuel to be mixed with a proportionate quantity of air, 35 the spindle being provided intermediate of its length with an enlargement 36 slidably engaging the supply passageway 27 and carrying a key-way 37 adapted to engage with a feather 38 on the upper end of the spray 40 nozzle C, the upper end of this spindle being threaded as shown at 39, so facilitating in the raising and lowering of the spindle to obtain the desired mixture.

The upper end of the spindle makes 40 threaded engagement with an adjusting member 40 carrying upper and lower end flanges and provided with a body portion substantially square which is adapted to slidably engage with the orifice 41 provided 45 in the spider 42 extending across the upper end of the neck 13, the said member being held in adjustable position by the spring 42^a surrounding the body portion and located between the lower flange and the 50 spider 42, which spring tends to provide the requisite pressure to seat the valve spindle in the seating provided in the supply passageway 27.

The taper of the valve spindle 35 relatively to the taper of the suction valve B and 55 spray nozzle C is such that the quantities of fuel and air are always in the same proportions, and any displacement of the several elements enumerated only permits the 60 volume to vary while the proportions remain constant.

The lower portion of the casing A is 65 enclosed by a removable cover 43 provided with an inlet conduit 44 through which air is designed to be delivered, the conduit car-

rying a butterfly valve 45 operatively mounted therein and designed to be held normally open under the action of a spring or the like, but capable of being actuated so that it may act as a throttle to limit the 70 supply of air passing through the conduit should such be found necessary or desirable.

Priming movement is given to the suction valve member B by means of a plunger 46 which is provided with enlarged ends, the 75 upper of which engages the lower face of the pinion 15 while the lower engages with the shorter arm of the bell crank 47 pivotally mounted on the cover 43 and designed to be actuated by the link member 48 simultaneously with the butterfly valve 45.

In Figs. 6 to 11 an alternative form of the invention is shown which differs from that already described in that the supply passageway 27 of the spray nozzle C extends to the top thereof and is provided with a conical valve seat with which the valve E engages. This valve is operatively connected to the upper arm of the angle spindle 49, the lower end of which is provided with 95 an enlarged head 50 having a groove 51 therein designed to engage with the crank arm 52 rigidly mounted on the lower arm of the crank member 53. The upper end of the crank member 53 is bifurcated and embraces the threaded nut 54 which makes threaded engagement with the slidably supported spindle 54^a provided on the end with a glass hard spherical end 55 adapted to engage with the inclined plane 56 pivotally 100 mounted on the projection 57 which is operatively connected to the lower end of the suction valve B.

By adjusting the nut 54, the spindle 54^a will be moved longitudinally so that the 105 spherical end 55 will engage the inclined plane 56 at an earlier or later period of the displacement of the suction valve B, so that the angular displacement of the crank member 53 is adjusted to permit of the rod 49 being moved upwardly to a greater extent and thus open the valve E to permit of more fluid being discharged through the passageways 26.

The inclined plane 56 carries a piece of 115 metal 58 inserted therein, which is glass hard and adapted to engage with the ball end 55 of the spindle 54 so that the wear on the working parts of the carburetor is thereby minimized. This inclined plane is further provided with a tongue 59 adapted to engage on its upper face with an adjustable set screw 60, while the lower face engages with a spring controlled plunger 61 thereby facilitating in adjusting the inclined plane 125 56 to the desired angle.

The valve E is designed to be retained or held in a normally closed position by the spring 70 engaging with the head 50 of the angle rod 49.

The casing A is provided with an integral projection 62 with which the set screw 63 makes threaded engagement, the point of the set screw being provided with a glass hard ball end 64 designed to engage with a glass hard piece of metal 65 inserted in the face of the projection 57 directly opposite the inclined plane 56.

The lower end of this carbureter is also 10 inclosed by a removable cover 43^a which is similar to that described with reference to Figs. 1 and 2, being provided with the air inlet conduit 44^a in which the butterfly valve 45^a is operatively mounted, the said butterfly 15 valve being held normally open under the action of the spring 46^a or the like.

The projection 57 is also inclosed by an auxiliary casing 65^a which is provided on its lower end with dowel pins adapted to 20 engage with the removable cover 43^a which carries a pivotally mounted resilient catch member 66 provided with a detent 67 on its free end designed to engage with a depression in the face of the casing 65^a.

25 The piston 21 carried by the suction valve B is, however, in this case provided with an annular groove in the upper face thereof into which molten metal may be poured, so facilitating in balancing the valve to the 30 required degree.

In the operation of the carbureter the bell crank 47 is operated so that the plunger 46 elevates the suction valve B, and simultaneously with this operation the butterfly 35 valve 45 is closed so that when the engine is started an undiluted charge of gasolene or other motive fluid is delivered through the radial orifices 26 to the tubular portions 13 from whence it passes through the neck 40 10 into the engine.

When the engine has once been started the crank member 47 returns under gravity to its normal position, while the butterfly valve 45 is opened under the action of a 45 spring or like member and the air after passing through the conduit 44 passes through the suction valve B where it intermixes with the fuel discharged from the radial passageways 26, the mixture passing 50 through the tubular portion 13 into the neck 10 and being delivered to the engine.

It will be clear that a portion of the air will pass through the ports 20 and acting on the under face of the piston 21 will 55 cause the suction valve B to remain floating, and this it will be understood is also brought about owing to the fact that the chamber 23 located above the piston 21 is in communication with the suction stroke 60 of the engine so that a partial vacuum is formed in the said chamber and there is no resistance to the upward motion of the suction valve.

The valve spindle 35 may be adjusted 65 through the medium of the pinion 16 which

meshes with the pinion wheel 15 on the suction valve B, thereby rotating the same, and during this operation the threaded portion 39 of the said spindle will be adjusted relatively to the adjusting member 40 located 70 at the upper portion of the tubular portion 13.

When the carbureter shown in Figs. 6 and 7 is in use the motive fluid passes from the supply chamber D through the passageways 32 and 33 into the supply passageway 27 from whence it passes through the radial passageways 26 and is delivered to the interior of the suction valve.

When an engine fitted with this carbureter 80 is being started, the butterfly valve 45^a is closed so that an undiluted charge of gasolene or motive fluid is delivered to the engine, and when the engine is once started the valve 45^a automatically opens under the action of the spring 46^a and the air passing through the conduit 44^a passes up through the suction valve B where it intermixes with the fuel issuing from the passageways 26 and is delivered to the tubular portion 13 90 and thence to the neck 10 of the carbureter from whence it passes to the engine.

The atmospheric pressure on the suction valve B tends to keep the same floating, and it will be clear that since the ball point 55 of the spindle 54 engages with the inset portion 58 of the inclined plane 56 the valve E on the upper end of the spray nozzle C is automatically controlled so that the amount of gasolene delivered through the radial 100 passageway 26 will be of a predetermined amount required by the engine.

From this description it will be seen that I have invented a carbureter wherein the suction valve controlling the supply of fuel 105 to the engine is automatically controlled by the suction of the engine, so that a predetermined quantity of fuel, requisite for the purposes required, is delivered to the engine so that a maximum of efficiency is obtained 110 from the same.

As many changes could be made in the above construction and many apparently widely different embodiments of my invention, within the scope of the claims, constructed without departing from the spirit or scope thereof it is intended that all matter contained in the accompanying specification and drawings shall be interpreted as illustrative and not in a limiting sense.

What I claim as my invention is:

1. A carbureter of the class described, comprising a casing, a floating and automatically actuated suction valve slidably mounted in the casing provided with a lower conoidal portion carrying a pinion, a manually operated pinion meshing with the said pinion, a spray nozzle located in the suction valve, a valve coating with the suction valve, threaded means connecting the last 130

said valve to the suction valve and means preventing the last said valve from turning with the suction valve as and for the purpose specified.

- 5 2. A carbureter of the class described, comprising a casing, a floating and automatically controlled suction valve operating in the casing and provided intermediate of its length with a piston slidably engaging 10 the inner periphery of the casing, a pinion integral with the lower end of the suction valve provided with ports, a manually operated pinion meshing with the said pinion, a spray nozzle located in the suction valve, a

valve coating with the spray nozzle adapted to control the flow of convertible fluid therethrough, adjustable threaded means operatively connecting the last said valve to the suction valve whereby on the actuation of the suction valve, the said valve is operated and means preventing the last said valve from turning with the suction valve. 15 20

In witness whereof I have hereunto set my hand in the presence of two witnesses.

EDMUND JOHN THOMPSON.
